(57) CLAIM

The ornamental design for a water float, as shown and described.

DESCRIPTION

FIG. 1 is a top plan view thereof wherein the water float is folded;

FIG. 2 is a bottom end view thereof wherein the water float is folded;

FIG. 3 is a bottom plan view thereof wherein the water float is folded

FIG. 4 is a top end view thereof wherein the water float is folded;

FIG. 5 is a right edge elevational view thereof wherein the water float is folded;

FIG. 6 is a left edge elevational view thereof wherein the water float is folded

FIG. 7 is a perspective view thereof wherein the water float is folded.

FIG. 8 is a top plan view thereof wherein the water float is unfolded;

FIG. 9 is right edge view thereof wherein the water float is unfolded;

FIG. 10 is a bottom plan view thereof wherein the water float is unfolded;

FIG. 11 is a left edge view thereof wherein the water float is unfolded;

FIG. 12 is a perspective view thereof wherein the water float is unfolded;

FIG. 13 is top end view thereof wherein the water float is unfolded; and,

FIG. 14 is a bottom end view thereof wherein the water float is unfolded.
